UNITED STATES PATENT OFFICE.

GERRIT VAN DAAM, OF BUFFALO, NEW YORK.

HYDROCARBON-BURNER.

1,260,836.

Specification of Letters Patent. Patented Mar. 26, 1918.

Application filed July 20, 1917. Serial No. 131,671.

To all whom it may concern:

Be it known that I, GERRIT VAN DAAM, a citizen of the United States, residing at Buffalo, in the county of Erie, State of New York, have invented a new and useful 5 Hydrocarbon-Burner, of which the following is a specification.

My invention relates to improvements in hydro-carbon burners. The object is to provide 10 improved means for generating a gas from the hydro-carbon, and improved means for delivering to the generator a steam jet for preventing the accumulation of carbon therein.

15 Referring to the drawings, which illustrate merely by way of example, suitable means for effecting my invention—

Figure 1 is a perspective view of a burner embodying my invention.

20 Fig. 2 is a part elevation and part section on an enlarged scale.

Fig. 3 is a part elevation and part section, showing needle valve control.

25 Fig. 4 is a sectional detail, on an enlarged scale, of a modification of needle valve control.

Fig. 5 is an elevation of same.

Fig. 6 is a sectional view of a double vaporizing tube.

30 Fig. 7 is a sectional view of a single vaporizing tube with wick.

Similar numerals refer to similar parts throughout the several views.

Referring to Fig. 1, the oil reservoir 9 is 35 connected by the pipe 10 to the T 11 which in turn is connected by the pipes 12 with the burners; such connections being controlled by the valves 35. A controlling valve 16^a is also provided between the reservoir 40 9 and pipe 10. A pipe 33 leads from the funnel 34 at the top of reservoir 9, to the bottom of said reservoir and delivers to pipe 10 just above valve 16^a but is not connected thereto.

45 Pipes 12 deliver to the chambered bodies 14 at points substantially above the bottom of said chambered bodies, whereby water pockets are formed below said intakes.

50 As the structures of the two burner elements are the same, one only will now be described. Connected with the chambered body 14 is pipe 15 leading upwardly through

the base 13 to the generator 16. From the opposite side of generator 16, conductor 17 leads to the nozzle 18 which is also supported by the base 13. The elbow formations 19 permit the proper spacing of conductors or pipes 15 and 17 on each side from the generator 16 and nozzle 18.

The supply of fuel to nozzle 18 is controlled by the valve 35. A further control of the discharge from nozzle 18 may be secured, if desired, by the needle valve 20 or 20^b as shown on Figs. 3, 4 and 5.

In Fig. 3 the valve 20 is operated by hand wheel 20^c. In Figs. 4 and 5 the needle 20^b is stationary, while the nozzle 18' is mounted on a threaded bearing and rotated by a worm gear 20^a as shown.

Beneath the nozzle structure 18 is provided the removable cleaning cap or cup 21. Above the nozzle 18 and adjacent the generator 16 is provided the spreader 22 for spreading the flame from nozzle 18.

Within the conductor 15 is provided a 75 tubing 23, open at the bottom and dipping into the liquid in the chambered body 14 and provided near the top with the vent 24 directed toward the generator 16, as shown in Fig. 2. This tubing is also shown 80 in Fig. 6, formed with two legs joined at a point well within the elbow formation, and provided with the vent 24, directed toward the generator 16. The lower ends of the tubing are open and dip into water 85 which accumulates in the pocket at the bottom of 14.

In Fig. 7 a single tube 25 is shown open at top and bottom and provided with a wick 26.

The base 13 is provided with a middle 90 horizontal portion 27, and vertically extending flanges 28 and 29 above and below said horizontal portion. The greater portion of the lower flange 29, between the two ends of the base, is cut away from an air space. 95 A number of apertures 30 are provided on the horizontal portion with upwardly extending flanges corresponding in height of the flange 28, other flanged apertures such as 31 and 32 form supporting collars for 100 securing the burner structure proper such as pipes 15 and the nozzle 18.

While the spreader member 22 is shown as suspended slightly below generator 16,

it may obviously be placed at any desired elevation with respect to the generator depending upon other conditions.

In operation—

- 5 By opening valves 15, one or both as desired, oil is permitted to flow through nozzle or nozzles 18, and down into the pan like formation of base 13, until a sufficient amount has accumulated therein, whereupon 10 the valves are closed and the oil in the base ignited. After the oil has burned for a short period sufficient to heat up the burner elements, the oil contained in the generator 16 and adjacent piping becomes vaporized 15 and upon opening the valves again the vapor will burn from said nozzles 18. The flame projecting against the spreader 22 will communicate increased heat to the generator 16, which will result in an extremely efficient 20 vaporization of the oil passing therethrough. The gas thus produced will burn with a clear intense flame free from smoke or odor.

For cleaning the burner and preventing 25 the accumulation of soot in the generator, a small quantity of water is poured into the funnel 34 which delivers through pipe 33 to pipe 10 through which it is conducted to chambered body 14 where it settles in the 30 pocket formed below the intake of pipe 12.

Within the pipe 15 is located the fine tube 23, which in Fig. 6, is shown with double legs 23', the bend being at the top and located in the elbow 19. In this bend is provided a vent 24' directed toward the generator 16. The lower ends of the tube 23' are open and dip into the water contained in the bottom of chambered body 14. As the structure becomes heated the water rises 40 in tube 23' and as it rises and approaches the hotter part of the tube it becomes vaporized, thereby expanding, and finally issuing as a fine jet through vent 24' into the generator 16. This vapor or steam 45 serves to cut any carbon formed in the generator 16 and prevents an accumulation of carbon therein. By adding a little water as above described, about once a day the generator is kept free and clean from soot.

50 In the alternative arrangement shown in Fig. 7 a single tube 25 is used provided with the wick 26. This serves to cause water to rise in the tube by the capillary action in the wick, and as the upper part of the tube 55 is subjected to great heat, it vaporizes and discharges into the generator in the manner described.

What I claim is:—

1. In a hydro-carbon burner, the combination of a pan shaped base, an upwardly projecting nozzle removably connected with the base, a supply pipe for hydro-carbon, a generator comprising an annular chambered body positioned above the nozzle and connected with the supply pipe, and a con-

70 tor from the generator to the nozzle and a spreader presenting a flame impinging surface adjacent the generator to spread the flame thereto.

2. In a hydro-carbon burner, the combination of a pan shaped base, having downwardly extending end flanges as a support therefor, an upwardly projecting nozzle removably secured to the base, a supply pipe, a generator comprising a chambered body 75 supported above the nozzle and connected with the supply pipe, a conductor from the generator to the nozzle and a spreader presenting a flame impinging surface slightly below the generator to spread the flame 80 thereto.

3. In a hydro-carbon burner the combination of a burner nozzle, a generator comprising a chambered body positioned above the nozzle, a conductor leading from a source 85 of supply to the generator and a conductor leading from the generator to the burner nozzle, a water pocket associated with the conductor leading to the generator, and means dipping into the water contained in 90 the water pocket for converting the water into steam or vapor and projecting the same into the generator.

4. In a hydro-carbon burner the combination of a burner nozzle, a generator comprising a chambered body positioned above the nozzle, a conductor leading from a source of supply to the generator and a conductor leading from the generator to the burner nozzle, a water pocket associated with the conductor leading to the generator, and means comprising a tube dipping into the water contained in the water pocket for converting the water into steam and projecting the same into the generator. 95

5. In a hydro-carbon burner the combination of a burner nozzle, a generator comprising a chambered body positioned above the burner nozzle, a conductor leading from a source of supply to the generator and a conductor leading from the generator to the burner nozzle, a water pocket associated with the conductor leading to the generator, and a tubing formed with two legs joined at the top and provided at its upper end with a vent directed into the generator and open at its lower ends and dipping into the water accumulated in the pocket as means for vaporizing and discharging steam into the 100 generator. 110

6. In a hydro-carbon burner the combination of a burner nozzle, a generator comprising a chambered body positioned above the burner nozzle, a conductor leading from a source of supply to the generator, a conductor leading from the generator to the burner nozzle, a water pocket associated with the conductor leading to the generator, means for conducting water to the water pocket, and means dipping into the wa- 115 120 125 130

ter contained in the water pocket for converting the water into steam and projecting the same into the generator.

7. In a hydro-carbon burner the combination of a burner nozzle, a generator comprising a chambered body positioned above the burner nozzle, a conductor leading from a source of supply to the generator, a conductor leading from the generator to the

burner nozzle, a water pocket associated with the conductor leading to the generator, means for conducting water through the fuel to the water pocket, and means dipping into the water contained in the water pocket for converting the water into steam and projecting the same into the generator. 15
